CLAIM

The ornamental design for a mounting clamp with support neck, as shown and described.

DESCRIPTION

FIG. 1 is a perspective view of the mounting clamp with support neck;

FIG. 2 is a top view of the mounting clamp with support neck shown in FIG. 1;

FIG. 3 is a side view of the mounting clamp with support neck shown in FIG. 2, the opposite side being substantially a mirror image thereof, except that the line to the right of the circular features on the clamp would not be seen;

FIG. 4 is a bottom view of the mounting clamp with support neck shown in FIG. 1;

FIG. 5 is a right end view of the mounting clamp with support neck shown in FIG. 1; and,

FIG. 6 is a left end view of the mounting clamp with support neck shown in FIG. 1.

The broken line portions of the disclosure are for illustrative purposes only and form no part of the claimed design.
